ELEVATOR SIGNAL AND CONTROL
SYSTEM

Harold W. Williams and Edgar M. Bouton, Chicago, Ill., assignors to Westinghouse Electric Elevator Company, Chicago, Ill., a corporation of Illinois

Application December 7, 1935, Serial No. 53,378

15 Claims. (C.I. 177—336)

Our invention relates to signal and control systems for elevators and more particularly to systems of this character which include means whereby intending passengers at the landings may effect the stopping of the cars at such landings.

One object of our invention is to provide a signal and control system which will promote the answering of calls and the loading and unloading of passengers in the most prompt and efficient manner.

Another object is to provide an elevator system in which the intending passengers may cause the appropriate car for their intended direction of travel to stop without any action on their part beyond selecting the approach they make to the bank of cars.

Another object is to provide a system in which the approach of an intending passenger through an appropriate entrance or a predetermined position to a bank of elevators at a floor will not only effect the stopping of the appropriate car for him at that floor but will also instantly operate a signal which will indicate to the intending passenger the hatchway door at which the car will stop so that he may walk directly to that door and be ready to enter the car upon its arrival.

Another object is to provide a system in which the appropriation of a stop call by a car for a floor will prevent any other car from receiving that call.

Another object is to provide a quota system for elevator groups in which the number of stop calls each car will receive during its trip will be limited by a predetermined number of intending passengers either at one floor or at several floors.

A further object is to provide an elevator system in which the leading car, after receiving stop signals from a predetermined number of intending passengers on a trip, will not receive any further stop calls on that trip but the next following car will receive such additional stop calls as are registered.

A further object is to provide a system which will prevent each of the cars from receiving stop calls for more than a predetermined number of passengers during an up trip or during a down trip.

It is also an object of our invention to provide a passenger counting means which will count only the incoming passengers at each floor.

The present invention includes, among other novel ideas, the provision of a plurality of light-

sensitive cells so arranged and connected that the normal movement of the intending passengers at the floors will result in effecting the stopping of the cars for the appropriate direction for such passengers and at the same time effect the instant operation of the floor lanterns to indicate which car will stop for the passengers, without the necessity of the passengers operating any push buttons or switches.

For a better understanding of the invention, reference may be had to the accompanying drawings, in which:

Figure 1 is a view in perspective of the entrance to a bank of elevator cars at a floor, and includes a plurality of light-sensitive devices for controlling the stopping of the cars and the operation of the floor lanterns in accordance with our invention.

Fig. 2 is a top plan view of the light-sensitive cell arrangement shown in Fig. 1.

Fig. 3 is a representation of a counting device for counting the number of passengers entering the entrance to the elevator landing.

Fig. 4 is a diagrammatic representation of a plurality of inductor relays and their inductor plates associated with each car for effecting its deceleration and stopping as it approaches a landing.

Fig. 5 is a representation of the contact segments and brushes on a floor selector for the cars.

Figs. 6, 7 and 8 collectively constitute a diagrammatic representation, in what is known as a straight line circuit, of the signal and control system employed in operating the elevator system serving the floor landing shown in Fig. 1; and

Figs. 6A, 7A and 8A collectively constitute an explanatory illustration of the relays embodied in Figs. 6, 7 and 8.

The illustration of the relays in Figs. 6A, 7A and 8A shows their coils and contact members disposed in horizontal alignment with their position in the straight line circuit of Figs. 6, 7 and 8, so that the reader may readily determine the identity of any relay, the number and kind of its contact members, and the position of its coil and its contact members in the straight line circuit. Inasmuch as the relays for car B are the same kind as used for car A, the car B relays have not been shown in Figs. 6A, 7A and 8A, thereby saving considerable space in the drawings.

For convenience in reading the drawings, Fig. 7 should be placed under Fig. 6; Fig. 8 under

Fig. 7; Fig. 6A beside Fig. 6; Fig. 7A beside Fig. 7 and under Fig. 6A; and Fig. 8A beside Fig. 8 and under Fig. 7A.

Referring more particularly to the drawings, 5 we have illustrated an elevator system embodying a bank of cars with the wiring diagram developed for two of the cars A and B. The cars are disposed for serving five floors or landings, similar to the landing shown in Fig. 1. The cars 10 are suitably suspended by cables 8 and B8 which pass over hoisting drums 9 and B9 respectively.

The relays for car B are given the same designation as those for car A with the letter B pre-fixed thereto. The letters U and D indicate the 15 up and the down direction. The prefix numerals indicate the floors. The suffix numerals indicate the contact members of the relays. For instance, the term B3UR3 indicates the contact members for the third floor in the up direction for the 20 call registering relay for car B.

Referring to the control system for car A (Fig. 6), the hoisting drum 9 is directly coupled to an armature 10 of a hoisting motor 11, the field winding 12 of which is connected for constant 25 voltage energization to a source of supply designated as the supply conductors L+1 and L-1. It may be noted that the supply conductors are extended throughout Figs. 6, 7 and 8 as L+2 and L-2, L+3 and L-3, L+4 and L-4, L+5 30 and L-5, and L+6 and L-6. These supply conductors are disposed to be controlled by a pair of line switches 13.

A variable voltage system of control is indicated as provided for operating the hoisting motor 11 wherein the armature 10 is connected in a 35 closed circuit with the armature 14 of a generator 15. The generator is provided with a separately excited field winding 16 and a cumulative series field winding 17. A resistor 18 is connected in the 40 circuit of the separately excited field winding 16 for controlling the speed of the generator. The armature 14 of the generator may be driven by any suitable driving motor (not shown). Inasmuch as driving motors for motor generator 45 sets of the Ward-Leonard type indicated, are old and well-known in the art, no further description thereof will be given.

A spring operated brake 5 controlled by a brake magnet 6 is provided for applying a braking effect 50 to the hoisting drum 9 when the car is brought to a stop, the brake magnet 6 being energized to release the brake when the car is running and being deenergized to apply the brake when the supply of power to the car is cut off.

The direction and speed of the hoisting motor 11 may be suitably controlled by controlling the 55 direction and the value of the excitation current supplied to the separately excited field winding 16 of the generator 15.

The direction of the excitation current for the 60 field winding 16 may be suitably controlled by means of an up direction switch U and a down direction switch D, while the value of the current supplied to the field winding may be controlled by means of a high speed relay V which 65 controls the resistor 19.

The operation of the up direction and the down 70 direction switches U and D, as well as the high speed relay V may be controlled by means of a switch CS in the car. This switch is so arranged that, if the car attendant moves it from its center position in a counter-clockwise direction, the up direction switch U will be energized to effect the moving of the car upwardly. If the 75 switch is moved from its center position in a

clockwise direction, the down direction switch D will be energized to effect the moving of the car downwardly. Hence, it is seen that the starting of the car in either direction is effected by the car attendant operating the switch CS for the direction desired.

The car may be decelerated and stopped level with any floor it serves by the attendant centering the car switch as the car arrives at the point from which it can be decelerated and stopped at 10 that floor.

Any suitable decelerating and stopping means may be employed which will effect this result in response to the centering of the car switch. As one example, I have illustrated an automatic inductor landing system similar to that disclosed in Patent No. 1,884,446, issued October 23, 1932, to K. M. White and G. K. Hearn, assignors to Westinghouse Electric Elevator Company.

The inductor landing system for car A includes a decelerating inductor relay E and a stopping inductor relay F for causing the car to be automatically decelerated from its high speed and brought to a stop at an exact level with the floor. The decelerating inductor relay E is mounted on the car A (Fig. 4) in position to cooperate with an inductor plate UE for the up direction and with an inductor plate DE for the down direction. The stopping inductor relay F is mounted on the car in position to cooperate with an up inductor plate UF and a down inductor plate DF. The inductor plates are constructed of magnetic material and are mounted in the hatchway in position to cooperate with and open the contact members of the inductor relays on the car when the relays are in an energized condition as the car approaches a stop at any landing.

For simplicity, only one set of inductor plates for one floor has been shown, but it will be understood that a set similar to that shown may be provided for each floor served by the car intermediate its upper terminal and its lower terminal. If desired, a set of inductor plates corresponding to the inductor plates UF and UE may be provided for the upper terminal floor and a set corresponding to inductor plates DE and DF may be provided for the lower terminal floor.

As shown, each inductor relay is provided with two sets of contact members. For an "up" stop, the contact members E1 of the relay E cooperate with the inductor plate UE in decelerating the car and the contact members F1 cooperate with the inductor plate UF in stopping the car after it is decelerated. For the down direction, the contact members E2 of relay E cooperate with the inductor plate DE to decelerate the car and the contact members F2 cooperate with the inductor plate DF in stopping the car.

The contact members just described are so connected with the up direction and the down direction switches and the car control circuits that, when the inductor relays are energized to decelerate and stop the car at a floor in the down direction, the contact members E2 will open as they pass the inductor plate for that floor and will thereby decelerate the car and the contact members F2 will open as they pass the inductor plate DF and thereby stop the car at the floor. The contact members E1 of relay E and the contact members F1 of the relay F are opened by the inductor plates UE and UF, respectively, when the stop is to be made in the up direction.

When the inductor relays are energized to decelerate a car to a stop, it is desired to maintain them in that condition until they operate 75

to bring the car to rest. A slow-down holding relay G is provided for this purpose.

After the inductor relays are energized for a stop, they will remain energized until restored, even when their contact members are opened by passage near the inductor plates. Therefore, an inductor restoring relay M is provided for deenergizing the inductor relays of the car after a stop has been made and also for so interlocking them that they can be energized only while the car is moving.

Centering of the car switch will energize the inductor relays, so the car attendant may, by centering his car switch effect the stopping of the car level with the next floor.

It will be obvious that the inductor plates for each floor must be located sufficiently in advance of that floor to permit slowing down and stopping of the car at that floor. It will also be obvious that the car attendant must center his car switch for a stop at a floor at some point before he arrives at the inductor plates for that floor. Inasmuch as these distances will vary in each system in accordance with the characteristics of the elevator, no definite distance can be here given, but any elevator engineer fairly well skilled in the art will be able to place the plates in their correct locations in each installation.

A door operating relay 45 is provided for effecting the closing of the hatchway door 23 for car A when the car leaves a landing after making a stop thereat. The relay 45 is controlled by the car switch CS. Inasmuch as the door operating mechanism to be controlled by the relay 45 is old and well known in the art, it is not shown in the drawings and no further description will be given.

A plurality of floor lanterns are provided at each floor to indicate to the intending passengers at the landings which cars will stop and their direction of operation. The up lanterns for car A at the lower terminal and the second, third and fourth floors are indicated respectively as 1UL, 2UL, 3UL and 4UL. The down lanterns for the upper terminal and the fourth, third and second floors are indicated as 5DL, 4DL, 3DL and 2DL.

As stated above, the car attendant may stop the car at any floor desired by centering the car switch as the car approaches that floor. However, in the present system it is desired to provide means by which the intending passengers at the floor landings can effect the stopping of the next approaching car for the direction they desire to travel, irrespective of the operations by the car attendants. In practicing our invention we effect this desired result in a novel manner by providing means whereby the approach of the passengers to the car entrances at a landing through an up entrance will stop the nearest approaching car for the up direction and through a down direction entrance will stop the nearest approaching car for the down direction. By the term "nearest approaching car" we mean that car whose position, direction of operation and distance from said floor will permit the car stopping means to stop it at that floor when it arrives thereat. In other words, it means the nearest car for the desired direction which is still capable of being stopped at the floor at which a stop call is registered at the time the call is registered.

In practicing our invention we provide means whereby the approach of the intending passengers at the floor landings will effect the stopping of the cars at such landings without any

additional action on the part of the passengers beyond directing their steps through an "up" entrance, or a "down" entrance in accordance with the direction they desire to travel. As shown in Fig. 1, (which may be taken as the third floor landing) each landing is provided with a plurality of hatchway doors 23, one for each of the cars. The entrance to the landing includes an "up" entrance 50 and a "down" entrance 51. An exit 52 is disposed between the up entrance 50 and the side wall 53 and an exit 54 is disposed between the down entrance 51 and the side wall 55. The entrances are suitably divided by standards 56, 57 and 58. The down passengers should pass through the "down" entrance 51, the up 15 passengers should pass through the "up" entrance 50 and the outgoing passengers should pass through the exits 52 and 54.

In order that the approach of the passengers through the "up" entrance or the "down" entrance at each landing may effect the stopping of the appropriate car for the corresponding direction, we have provided a plurality of passenger operated controls or light sensitive devices mounted on the standards 56, 57 and 58. These 25 control devices comprise a pair of light-sensitive cells UQ and UT located on the upper part of the standard 56 and a pair of light-sensitive cells DQ and DT located on the upper part of the standard 58. The cell's Ut and DT may be called 30 call preparing cells and the cells UQ and DQ may be called call operating cells. A suitable lamp 60 is disposed in the upper portion of the standard 57 for the purpose of throwing light rays toward the light-sensitive cells UQ and UT on the up standard 56 and the light-sensitive cells DQ and DT on the down standard 58. A plurality of suitable lenses 61 are disposed adjacent to the lamp 60 for the purpose of concentrating a stream of light rays directly upon each of the 40 light-sensitive cells. These light rays are indicated by the numerals 62, 63, 64 and 65 (Fig. 2).

The light-sensitive cells are associated with amplifiers and relays in such manner that a person going to the elevators and passing through the "up" entrance 50 will intercept first the light rays 63 from the lamp 60 to the cell UT and then intercept the light rays 62 from the lamp 60 to the cell UQ and thereby effect the registration of an up stop call for the nearest approaching car. The lamp rays and their relay are arranged in such order that the persons passing out through the up entrance 50 will not cause the registration of a stop call. Similarly, if a down passenger enters the elevator corridor 55 through the down entrance 51, he will first intercept the light rays 65 and then the light rays 64 and thereby effect the registration of a down stop call for the nearest approaching down car. Also, if the passenger walks out through the entrance 51, the arrangement of the light ray cells and their associated relays are such that no down call will be registered.

The lower portion of Fig. 8 of the drawings represents the circuits for the lamp 60, the light sensitive cells, and their associated amplifiers and relays. The amplifiers associated with these relays are respectively indicated by the numerals 70, 71, 72 and 73. The relays associated with the up light-sensitive cells UT and UQ are respectively a call preparing relay 3UW, a call operating relay 3UX and a call preventing relay 3UY. The relays associated with the down cells DT and DQ are a call preparing relay 3DW, a call operating relay 3DX and a call preventing relay 3DY. 75

- It is to be understood that although any suitable system of light-sensitive devices may be utilized in our present invention, the arrangement indicated in the drawings is believed to be preferable and to embody certain novel features as to the provision of the relays and their connections with the cells so that the system will respond only to the movement of intending passengers through the entrances toward the elevators and will not respond to the movements of passengers away from the elevators. It is also to be understood that the light-sensitive system shown in the lower portion of Fig. 8 is for the third floor only, and that a similar system is provided for each of the other intermediate floors. If desired, a pair of light-sensitive cells DT and DQ may be provided for the upper terminal and a pair of light-sensitive cells UT and UQ may be provided for the lower terminal.
- The means for registering stop calls for car A includes a plurality of call registering relays, those for the up calls at the first, second, third and fourth floors being indicated by the numerals 1UR, 2UR, 3UR and 4UR, and those for down calls at the fifth, fourth, third and second floors being indicated by reference numerals 5DR, 4DR, 3DR and 2DR, respectively. Each call registering relay is provided with a cancellation coil whereby a car in answering a call may cause the call to be cancelled and its call registering relay to be restored to its normal condition. The cancellation coils are indicated at 1UC, 2UC, 3UC and 4UC for the up direction, and as 5DC, 4DC, 3DC and 2DC for the down direction. The relays enumerated are for car A, and it is to be understood that each car is provided with its own call registering relays.

In order that the call registering relays may be effective to stop the car, a stopping relay S is provided for energization by the joint action of the call registering relay for a floor and the approach of the car within a predetermined distance of that floor. The stopping relay for car A is indicated by the reference S and when it is energized it closes a circuit for energizing the inductor relays E and F to effect the stopping of the car in the same manner as they may be energized by the centering of the car switch.

The relay S may also be called a means functionally related to the stopping of the car because it may be used to operate a signal device 103 in the car to indicate to the car attendant that he should immediately center his car switch for a stop at the next floor at which the car can be stopped.

In the present system it is desired to have the floor lanterns light to indicate which car will stop at a landing as soon as a stop call at that landing is registered by the approach of an intending passenger to the elevator doors, so that the passenger will know immediately which car will stop for him and keep on walking toward it until he reaches the hatchway door for that car, where he will be ready to board the car as soon as it arrives. It is also desirable to provide that only the nearest approaching car shall receive the registered call.

In order to accomplish these purposes, we have provided the system with a plurality of zoning relays (Figs. 7 and 8) designated as 1UZ, 2UZ, 3UZ and 4UZ for the up direction and 5DZ, 4DZ, 3DZ and 2DZ for the down direction. These zone relays are common to all cars and divide the complete round trip shaft travel of all cars into as many signal zones as there are cars operating.

They assign one zone to each car. That zone is the zone in advance of that car's motion up to the next car in front of it. The zone for each car is elastic and keeps moving along with the car, its length being determined by the position of the car itself and by the position of the next car ahead. The zone relays are operated by the cars in accordance with their position. For car A, the zone circuit controlled by the zone relays is designated as 61; that for car B as 66 (Fig. 7). 10

After a stop call is registered on a call registering relay of a car, it is desirable to prevent any other car from picking up the same registered call. A plurality of preventing relays are provided for this purpose. They make the system selective and keep more than one car from getting a call. The preventing relays are common to all cars and are designated 1UP, 2UP, 3UP and 4UP for the up direction, and 5DP, 4DP, 3DP, and 2DP for the down direction.

In the operation of elevators, it is desirable to prevent overcrowding of the cars. Therefore, we have provided a counting means or relay responsive to the registration of stop calls and to the passage of intending passengers through the "up" and the "down" approach entrances leading to the cars at each floor for limiting the number of stop calls registered for any car during one trip between terminals in accordance with a predetermined number of passengers. This means comprises a counting device 75, as shown in Fig. 3. The counting device is so connected with the control system that when a predetermined number of intending passengers have caused it to be operated, it disconnects the car with which it is associated from the zoning system and from receiving any further stop calls from the passengers until the car reaches its terminal and resets the counting device for the next trip. An "up" counting relay for up trips and a "down" counting relay for down trips are provided for each car.

The "up" counting relay for car A comprises a counting coil UH and associated counting mechanism U75 including a pawl 76 operated by the coil UH, a ratchet wheel 77 operated by the pawl, a cam 78 on a shaft 80 operated by the ratchet wheel, and two pairs of contact members UH1 and UH2 disposed to be opened by the cam member when it reaches a predetermined position. The pawl 76 moves the ratchet wheel and the cam one step forward each time it is operated by an impulse of the coil UH responsive to the entry of one person through an entrance corresponding to the direction of the counting relay. A lug 84 prevents the cam 78 from going beyond the point at which it opens the contact members. Usually each counting relay is set or adjusted for a less number of passengers than its car will hold. For instance, if a car will hold twelve passengers, the device may be set for ten, so that extra passengers at the floors may be accommodated. A restoring coil UK is provided for restoring the counting device to its normal condition when the car reaches either terminal. The coil UK is energized temporarily by a limit switch UL operated by the arrival of the car at the upper terminal, and, when energized, withdraws a pawl 101 which permits the cam 78 to return to its starting position under the action of a biasing spring 83 and be ready for counting the intending passengers on the next up trip of car A. Inasmuch as the counting mechanism 75 included in the counting relay UH is the same in each 75

counting relay, only that for relay UH has been shown in detail (Fig. 3).

When the cam moves forward a predetermined number of steps, say ten, it opens the contact members UH1 and UH2 to prevent any additional passengers registering up calls for car A on that trip. A set screw 82 is provided for so adjusting the cam that it will require a more or less number of passengers to move it to the predetermined point at which it will open the contact members UH1 and UH2.

In order that the various control circuits for the floor lanterns, relays, etc., may be connected in accordance with the position of the cars with respect to the floors they serve, car A is provided with a floor selector SE with its contact segments and brushes arranged, as shown in Fig. 5. Inasmuch as floor selectors are old and well known in the art, it is not deemed necessary to show or describe them in detail in this application. However, the outlined plan shown in Fig. 5 will indicate clearly the number of contact segments and contact brushes necessary in the floor selector for car A. Car B will also be provided with a similar floor selector.

The floor selector for car A is provided with a set of up contact segments and a set of down contact segments, arranged according to the floors, and disposed to be engaged by cooperating up brushes 30 to 33, inclusive, and down brushes 40 to 43, inclusive. The brushes are mounted upon and insulated from a movable arm SM. The movable arm will be operated in accordance with movements of the car by means of a screw shaft 85 which may be driven by some part of the operating mechanism (not shown) of that car. The frictional engagement between the arm SM and its operating screw shaft 85 will cause the arm to bear upon the "up" contact segments when the car is travelling upwardly and upon the "down" contact segments when the car is travelling downwardly, it being understood that the arm will tilt from one position to the other when the direction of operation of the car is reversed. For a more complete detailed description of the type of floor selector employed, reference may be had to the Smalley and Reiners Patent No. 634,220, granted October 3, 1899.

The group of up contact segments designated as *a* under the brush 30 completes circuits for energizing the stopping relay to effect the stopping of the car when a stop call has been registered and the car is approaching within slow-down distance of the floor from which the call is registered.

The group of "up" contact segments designated as *b* under the brush 31 are disposed to energize the cancellation coils on the call registering relays when the car makes a stop at a floor in answer to a registered call.

The group of "up" contact segments designated as *c* under the up brush 32 are provided for energizing the zone relays in accordance with the position of car A. The brush 32 should be large enough to bridge the contact segments when passing from one to another to maintain the passing zone relay energized until the approaching zone relay is energized.

The group of "up" contact segments designated as *d* under the contact brush 33 are provided for feeding and energizing the zone circuits defined by the operation of the zone relays. The brush *d* should be large enough to bridge the contact segments when passing from one to another. The brushes 32 and 33 should also be spring

mounted and so adjusted that the brush on one side will engage its contact segments before the brush on the other side disengages when the selector arm tilts from the up to the down side or from the down to the up side.

The contact segments on the down side of the floor selector are engaged by the down brushes 40 to 43, inclusive, when the car is descending and correspond to the contact segments just described for the up direction, those marked *e* being the "down" stopping segments; *f* the "down" call cancellation segments; *g* the "down" zone relay segments; and *h* the "down" zone feed segments.

Car B is provided with a similar floor selector 15 which is not shown in the drawings, except that the contact segments and brushes are indicated in the diagrammatic representation of the control circuits in Figs. 6, 7 and 8.

Inasmuch as the control system for car B is 20 similar to that just described for car A, a detailed description thereof will not be given.

The invention may be best understood from an assumed operation of the apparatus shown in the drawings.

It will be assumed that car A is standing at the second floor on an up trip, that car B is standing at the fourth floor on a down trip, and that the line switches 13 (Fig. 6) are closed to prepare the control systems of both cars for 30 operation.

It will also be assumed that the counting devices are adjusted to prevent the registration of calls on a particular car during any one trip after ten passengers have entered the landings 35 during that trip for the direction of that trip.

Inasmuch as car A is at the second floor on an up trip, its down floor selector brush 32 is disposed on the contact segment 2c (see upper portion of Fig. 8), thereby energizing the zone relay 40 2UZ by a circuit extending from the supply conductor L+5 through the contact members UH2, brush 32, contact segment 2c, and coil 2UZ to the supply conductor L-5. At the same time, the down brush B42 of car B is disposed on the contact segment B4g thereby energizing the down direction zone relay 4DZ. The energized zone relay 2UZ opens its contact members 2UZ1 and 2UZ2 and the energized zone relay 4DZ opens its contact members 4DZ1 and 4DZ2. The opened 50 contact members 2UZ1 and 4DZ1 are disposed in the zone circuit 67 of car A and therefore divide that circuit into two portions, one portion being a signal zone for car A and the other portion being dead. The signal portion includes the 55 closed contact members 3UZ1, 4UZ1 and 5DZ1 and is rendered alive by the engagement of brush 33 with the zone feed contact segment 2d so that stop calls at the floors included in this circuit may be registered for car A. Inasmuch as the 60 other portion of the zone circuit 67 is cut off by the open contact members 2UZ1 and 4DZ1, that portion is dead and no calls can be registered through it.

The opening of the contact members 2UZ2 and 65 4DZ2 in the zone circuit B67 of car B divides that circuit into an energized portion and a deenergized portion. The energized portion includes the closed contact members 3DZ2, 2DZ2 and 1UZ2 and is rendered alive by the down zone feed brush 70 B43 being disposed on the contact segment B4h so that any stop call at the floors included in this live section may be registered for car B. The signal zones for the cars are now defined by the zone relays so that each car will receive stop calls 75

for only its own signal zone without affecting the other car in any way.

- It will be assumed now that an intending up direction passenger enters the up gate 50 at the third floor. The passenger in walking through this up entrance intercepts first the light rays 63 and next the light rays 62. As shown in the lower portion of Fig. 8, the interception of the light rays 63 extending from the lamp 60 to the light sensitive cell UT affects its amplifier 70 to cause operation of the up call preparing relay 3UW by a circuit extending from the winding 93 of the transformer TR through conductor 94, the coil 3UW, contact members 3UY1, the amplifier 70 and conductor 95 to the transformer winding 93. The energized relay 3UW closes its contact members 3UW1, 3UW2, 3UW3, 3UW4, and 3UW5, and opens its contact members 3UW6. The closing of the contact members 3UW3 and 3UW4 prepare the call registering relays 3UR and B3UR on cars A and B for operation. The closing of the contact members 3UW1 and 3UW2 prepare the call counting devices of cars A and B for operation. The closing of the contact members 3UW5 prevents operation of the relay 3UY. The closing of the contact members 3UW6 prepares the relay 3UX for operation. As the passenger continued through the entrance and intercepted the light ray 62, he caused the light sensitive cell UQ to so affect the amplifier 71 that the call operating relay 3UX is energized by a circuit extending from the transformer winding 93 through conductors 94 and 96, the contact members 3UW5, the coil 3UX, amplifier 71 and conductor 95 to the transformer winding 93. The energized call operating relay 3UX closes its contact members 3UX1, 3UX2, 3UX3 and 3UX4. The closing of the contact members 3UX3 energizes the up call registering relay 3UR for car A at the third floor by a circuit extending from the supply conductor L+3 through the contact members 3UW3 and 3UX3, the coil 3UR, the contact members 3UP1, junction point 97, the contact members 3UZ1, junction point 98, contact segment 2d and up zone feeding brush 33 and the contact members UH1 to the supply conductor L-3. The energized relay 3UR closes its contact members 3UR1, 3UR2, 3UR3, 3UR4 and 3UR5. The closing of the contact members 3UR4 establishes a self-holding circuit for the relay 3UR and the up stop call registered by the up passenger at the third floor will now remain registered until it is answered by car A stopping at that floor in the up direction and energizing the cancellation coil 3UC. The closing of the contact members 3UR1 connects the stopping contact segment 3a of car A to a source of supply represented by the supply conductor L-1. Inasmuch as the call registering relay 3UR has been operated to energize the contact segment 3a, the stopping relay S will be energized to effect the stopping of the car when it arrives within stopping distance of the third floor.

The closing of the contact members 3UR3 completes a circuit for lighting the up floor lantern 3UL for car A at the third floor, which circuit extends from the supply conductor L+3 through the lamp, the contact members 3UR3 and conductor 100 to the supply conductor L-3. The lighting of this lamp is effected immediately with the registration of the up stop call at the third floor and therefore the passenger is immediately informed as to which car will stop for him so that he may at once proceed to the hatchway door corresponding thereto and be ready to board

the car when it arrives and stops for him. The lamp remains lighted until the call is cancelled.

The closing of the contact members 3UR5 (Fig. 8) energizes the preventing relay 3UP by a circuit extending from the supply conductor L+6 through the contact members 3UR5 and the coil 3UP to the supply conductor L-6. The energized relay 3UP opens its contact members 3UP1 and 3UP2. The opening of the contact members 3UP2 (Fig. 7) will prevent the registration of a stop call on the registering relay B3UR for car B at the third floor in the event that car B passes car A and thereby operates the zone relays to place that floor in the signal zone of car B instead of car A. The opening of the contact members 3UP1 in the circuit of the registering relay 3UR has no effect on that relay at the present time because it is now provided with the holding circuit extending through the contact members 3UR4 and 3UR3.

Therefore it will be apparent that when a passenger walks through the correct entrance toward the elevator, his action registers a stop call for his car for that floor and lights the correct floor lantern to tell him at which door his car will stop, so that he may continue toward it and be ready to get on as soon as it arrives.

If no other passengers desire to ride at this time, the car will stop, take on its passenger and leave in usual order. In other words, it is not necessary to have more than one intending passenger to cause a car to make a stop.

As stated before, however, it is desirable to prevent a car from receiving stop calls for too many passengers, that is, each car should have a quota and not have to carry over a selected number of passengers during each trip. For this reason, the system is provided with the counting relays and the call registering relay closed its contact members 3UR2 when the call was registered on it.

The closing of the contact members 3UR2 (Fig. 6) energizes the up counting coil UH of car A by a circuit extending from the supply conductor L+1 through contact members 3UR2, 3UW1 and 3UX1 and the coil UH to the supply conductor L-1. As shown in Fig. 3, and as previously described, the energization of the counting coil UH causes it to pull upward on the counting pawl 16 which thereupon rotates the counting ratchet 17 to move the cam 18 one step (corresponding to one passenger) toward opening the contact members UH1 and UH2. The counting coil UH is energized only an instant and then drops its core downwardly but the latch 101 attached to the core of the restoring coil UK engages the ratchet 17 and holds it in the position to which it has been moved by the pawl 16. By this operation of the counting device, it is seen that the passage of an intending up passenger first registers an up stop call on the registering relay 3UR and then actuates the counting relay UH to move its cam 18 one step, representing the count of one passenger for car A. The counting device of car B is not affected because the call is not registered on the registering relay of car B and consequently the contact members B3UR2 are open in the circuit of the counting coil BUH of car B.

As long as the stop call remains registered on the third floor for car A, the contact members 3UR2 in the circuit of up counting coil UH will remain closed and therefore the coil will be actuated again each time another passenger walks through the up entrance at the third floor. For instance, it will be assumed that a second in-

tending passenger passes through the up passage-way 50 at the third floor for the purpose of making an up trip. This second passenger first intercepts the light rays 63 and then the light rays 62. 5 The interception of the light rays 63 energizes the relay 3UW and the interception of the light rays 62 again energizes the relay 3UX as previously described. The energization of these two relays again closes their contact members 3UW/10 and 3UX1 thereby again energizing the up counting relay UH (Fig 6) which raises the pawl 76 thereby moving the ratchet wheel 77 and associated cam 79 a second step toward opening the contact members UH1 and UH2. By this it is 15 seen how the counting relay UH is operated, by intending passengers passing through the entrance to the cars, in such manner that each passenger for the up direction is counted on the counting device by moving the cam one step forward. That is, the cam moves a step forward for each passenger.

It will be assumed now that the quota for car A has been set at ten passengers and that twelve more passengers pass through the up entrance 50 for an up trip. As they pass through, they intercept the light rays and effect the operation of the counting relay UH, as previously described, up until the time the tenth passenger passes through. At this point, the cam 79 has been 30 moved a sufficient number of steps to open the contact members UH1 and UH2 to prevent the registration of any more "up" stop calls for car A while it is on its present up trip.

The opening of the contact members UH1 disconnects the up zone feeding brush 33 of car A from the supply circuit L-3 and, therefore, no more up stop calls for car A can be registered by intending passengers during the present up trip of car A, because no energy will now flow through the call registering relays of car A even if the contact members indicated by UW and UX therein are closed. At the same time, the opening of the contact members UH2 disconnects the car A from the zone circuit operation so that car A 40 will not now operate to include itself in the signal zone circuits.

It will be assumed now that an intending up passenger at the fourth floor passes through the up entrance 50 at that floor and into the elevator corridor for the purpose of making an up trip. As this passenger moves through the light rays 63 and 62 at the fourth floor, he operates the call preparing relay 4UW and the call operating relay 4UX for the fourth floor in the same manner as the corresponding relays 3UW and 3UX were 55 operated for the third floor when the up passengers entered the third floor corridor.

The energized relay 4UW closes its contact members 4UW1, 4UW2, 4UW3, 4UW4 and 4UW5 60 and opens its contact members 4UW6. The closing of the contact members 4UW3 and 4UW4 prepare the call registering relays 4UR and B4UR on cars A and B for operation. The closing of the contact members 4UW1 and 4UW2 prepare 65 the call counting devices of cars A and B for operation. The closing of the contact members 4UW5 prevents operation of the relay 4UY. The opening of the contact members 4UW6 prepares the relay 4UX for operation.

The energized relay 4UX closes its contact members 4UX1, 4UX2, 4UX3 and 4UX4. The closing of the contact members 4UX3 in the circuit for the call registering relay 4UR of car A does not energize that relay to register a call thereon because of the open contact members UH1 in the

circuit to brush 33. However, the closing of the contact members 4UX4 completes a circuit for energizing the call registering relay B4UR of car B to register an up stop call at the fourth floor for car B. This circuit extends from the supply conductor L-4 through the contact members 4UW4, 4UX4, coil B4UR, the contact members 4UP2 to zone circuit B61, and thence through the contact members 4UZ2, 3UZ2, 2UZ2, 1UZ2, 2DZ2 and 3DZ2, contact segment B4h, brush B43 10 and the contact members BDH1 to supply conductor L-4. This circuit is now possible because the open contact members UH2 for car A have deenergized the zone relay 2UZ and consequently opened its contact members in the zone 15 circuits. By the foregoing, it is seen that the up stop call at the fourth floor is not registered on car A because that car's quota of passengers has entered the corridor at the third floor and has caused the counting relay UH for car A to so 20 operate as to prevent that car from receiving any further calls. The call is registered on car B because that is the next car to follow car A on an up trip.

The energized call registering relay B4UR closes 25 its contact members B4UR1, B4UR2, B4UR3, B4UR4 and B4UR5. The closing of the contact members B4UR1 energizes the stopping contact segment B4a for car B so that when car A approaches the fourth floor in the up direction, its stopping relay 30 BS will be energized to stop it at the fourth floor. The closing of the contact members B4UR2 prepares the circuit for the up counting coil BUH of car B. The closing of the contact members B4UR3 completes a circuit for the up direction 35 floor lantern B4UL for car B at the fourth floor to tell the intending passenger instantly that car B will stop for him on his up trip so that he can walk directly to the hatchway door for that car and be ready when it arrives and stops. The 40 closed contact members B4UR4 provide a self-holding circuit for the registering relay B4UR. The closed contact members B4UR5 energize the up preventing relay 4UP to open its contact members 4UP1 and 4UP2 for the purpose of preventing 45 any other car from taking its registered call away from car B.

Turning now to the operation of the energized call operating relay, we find that the closing of its contact members 4UX1 in the circuit of the 50 counting relay for car A had no effect because of the open contact members 4UR2 of the call registering relay for car A in that circuit. However, the closing of the contact members 4UX2 in the circuit of the up counting coil BUH for car B 55 completes a circuit for energizing that coil. This circuit extends from the supply conductor L-2 through the contact members B4UR2, 4UW2 and 4UX2, and the coil BUH to the supply conductor L-2. The energized coil BUH operates to rotate 60 the up counting device for car B one step toward the quota for car B. The foregoing description of the registration of calls for the cars shows how the quota for car A may be filled at one floor and how subsequent up calls while car A is still on 65 its up trip will be registered for the next following car, which, in this case is car B.

At this point, it will be assumed that the attendant on car A moves the car switch CS in a counterclockwise direction to start that car upwardly to the top floor. This action closes the contact members a and e of switch CS thereby energizing the door closing relay 45 to effect the closing of the car gate (not shown) of car A and the hatchway door 23 at the second floor. The 75

energization of the relay 45 also closes its contact members 45-1 in the circuit to the brush 41 of car A (Fig. 7) so that the cancellation coil 2UC of car A for the second floor is energized to cancel any call that may have been registered on the call registering relay 2UR for that car at that floor.

A further movement of the switch CS closes its contact members *a* and *f* thereby energizing the up direction switch U by a circuit extending from the supply conductor L-1 through conductor 87, the contact members *a* and *f* of switch CS, the contact members F1, coils U and M and the door and gate contact members 88 to the supply conductor L-1. The energized relay M closes its contact members M1 to prepare the stopping inductor relays for operation and opens its contact members M2 (Fig. 7) in the circuit to brush 41 to prevent the cancellation of any registered calls until car A makes its next stop.

20 The energized up direction switch U closes its contact members U1, U2, U3, U4 and U5. The closing of the contact members U1 energizes the brake coil 6 (Fig. 6) and releases the brake 5 from the hoisting drum 9. The closing of the contact members U2 and U3 energizes the field winding 16 of the generator 15 by a circuit extending from the supply conductor L-1 through the contact members U2, winding 16, the contact members U3 and the resistor 19 to the supply conductor L-1, thereby causing the generator 15 to supply sufficient energy to the motor 11 to operate the hoisting drum 9 in running the car upwardly. The closing of the contact members U4 energizes the high speed relay V by a circuit extending from the supply conductor L-1 through the contact members U4 and E1 and the coil V to the supply conductor L-1. The energized relay V closes its contact members V1 thereby short circuiting the resistor 19 and causing the hoisting motor 11 to be operated at high speed. The energized relay V also opens its contact members V2 thereby preventing energization of the stopping inductor relay F until after the car has been decelerated to its normal landing speed.

45 The closing of the contact members U5 provides a self-holding circuit for the switch U for the purpose of maintaining it in operation until the stopping inductor relay has been energized and operated to stop the car at a landing.

50 As the car moves toward the third floor, its up brush 30 engages the energized contact segment 3a thereby energizing its stopping relay S to stop the car at the third floor in answer to the stop call registered at that floor. The circuit for the relay S extends from the supply conductor L-1 through the coil S, brush 30, contact segment 3a and the closed contact member 3UR1 to the supply conductor L-1. The energized relay S closes its contact members S1 thereby energizing the decelerating inductor relay E and the inductor holding relay G to decelerate the car. As the car approaches still closer to the third floor, the energized inductor relay E passes the up conductor plate UE for the third floor and is thereby caused to open its contact members E1 to deenergize the high speed relay V. The deenergized relay V opens its contact members V1 thereby reinserting the resistor 19 in the circuit for the field winding 16 to decrease the speed of the hoisting motor 11 and the car to landing speed. The deenergized relay V also closes its contact members V2 thereby energizing the stopping inductor relay F.

75 As the car approaches still more closely to

the third floor, the energized inductor relay F passes the up conductor plate UF and is thereby operated to open its contact members F1 which deenergizes the up direction switch U and the inductor restoring relay M. The deenergized up direction switch U opens its contact members to apply the brake 5 and stop the motor.

As the car arrives and stops at the third floor, the attendant centers the car switch for the purpose of deenergizing the relay 45 to permit the opening of the car gate and the corresponding hatchway door. The door is thereupon opened so that the intending passengers may step aboard the car. As the car leaves the third floor, the relay 45 is energized to close the door and, therefore, closes its contact members 45-1 which completes a circuit for energizing the cancellation coil 3UC of the call registering relay 3UR thus cancelling the up call registered at the third floor.

20 As car A arrives and stops at the top floor, its limit switch UL is operated to energize the reset coil DK to withdraw the pawl 101 in the counting device and thereby permit the cam 18 to return to its normal position under the biasing effect of the spring 83. The counting relay UH of car A is now reset to start a new quota for car A on its next up trip.

25 It will be assumed now that the attendant on car B moves his car switch BCS in a clockwise direction thereby energizing his down direction switch BD and causing the car B to move downwardly. It will also be assumed that he stops the car at the lower terminal and starts on an up trip. As car B approaches within stopping distance of the fourth floor, its up brush B30 engages the contact segment B4a which was energized by the registration of the up call at the fourth floor. The engagement of the brush B30 and the segment B4a will cause the stopping of the car at the fourth floor to take on the waiting passenger at that floor in the same manner that car A was stopped at the third floor. After the waiting passenger enters the car B, it is moved on up to the upper terminal where its arrival 45 causes the operation of the up limit switch BUL which energizes the counting cancellation call coil BUK to deenergize and restore the counting coil BUH for car B to its normal condition for counting the up passengers who register calls 50 for car B on its next up trip.

30 It will now be assumed that car A is moved down to the fourth floor. With car B at the top floor and car A on a down trip at the fourth floor, the zone relays 4DZ and 5DZ are energized 55 to open their contact members so that the signal zone for car A extends from the fourth floor to the bottom terminal and up to the top terminal while the signal zone for car B extends only to car A at the fourth floor ahead of it.

35 It will be assumed now that an intending down passenger at the third floor passes through the "down" entrance 51, thereby first intercepting the light rays 65 and next the light rays 64 for that floor. The interception of the light rays 65 causes the light sensitive cell DT to so affect its amplifier 72 as to complete a circuit for energizing the call preparing relay 3DW. The energized relay 3DW closes its contact members 3DW1 through 3DW5 and opens its contact members 3DW6. The closing of the contact members 3DW3 and 3DW4 prepare the down call registering relays of cars A and B at the third floor for operation. The closing of the contact members 3DW5 prevents energization of the call 75

5 preventing relay 3DY. The closing of the contact members 3DW1 and 3DW2 prepare the counting relays DH of car A and BDH of car B for operation. The opening of the contact members 3DW6 prepare the call operating relay 3DX for operation. The interception of the light rays 64 now affects the amplifier 73 to effect the energization of the call operating relay 3DX to close its contact members 3DX1, 3DX2, 3DX3 and 10 3DX4. The closing of the contact members 3DX3 causes the energization of the down call registering relay 3DR for car A at the third floor by a circuit extending from the supply conductor L-3 through the contact members 3DW3, 3DX3, 15 3DR and contact members 3DP1 to the zone circuit 67 and thence through the contact members 3DZ1, the contact segment 4h, and the contact brush 43 and contact members DH1 to the supply conductor L-3. The energized relay 3DR 20 closes its contact members. The closing of the contact members 3DR4 establishes a self-holding circuit for the relay 3UR and the down stop call by the intending down passenger at the third floor is now registered for car A and will now remain 25 registered for that car until it is answered by that car. The closing of the contact members 3DR1 connects the stopping contact segment 3e of car A to the supply conductor L-1. This energizes the segment 3e so that the stopping relay S of 30 car A will be energized to stop that car when it arrives within stopping distance of the third floor.

35 The closing of the contact members 3DR3 completes a circuit for lighting the down floor lantern 3DL for car A at the third floor to instantly notify the intending passenger the hatchway door at which the appropriate car will stop for him.

40 The closing of the contact members 3DR5 energizes the preventing relay 3DP to open its contact members and thereby prevent the registration of a stop call on the registering relay B3DR for car B at the third floor until the present registered call at that floor for car A is answered.

45 The closing of the contact members 3DR2 energizes the down counting coil for relay DH of car A by a circuit extending from the supply conductor L-1 through the contact members 3DR2, 3DW1, and 3DX1 and the coil DH to the supply conductor L-1. The energization of the counting coil DH causes it to operate its counting mechanism corresponding to a count of one passenger. It will be assumed that six other down passengers also step through the down entrance 51 at the third floor and thereby operate the counting relay DH to effect operation of its counting mechanism accordingly. This will make a total of seven persons at the third floor so actuating the counting mechanism of relay 50 DH as to move its cam seven steps toward the position at which it will open its cooperating switches when its quota of ten has been registered upon it.

55 It will be assumed now that an intending down passenger passes through the down entrance 51 at the second floor and into the elevator corridor for the purpose of making a down trip. As this passenger moves through the light rays 65 and 66 at the second floor, he operates the call preparing relay 2DW and the call operating relay 2DX for the second floor in the same manner as the corresponding relays 3DW and 3DX for the third floor were operated when the down passengers entered the landing at the third floor.

70 75 The energized relay 2DW closes its contact

members 2DW3 and 2DW4 to prepare the call registering relays 2DR and B2DR for cars A and B for operation. The closing of the contact members 2DW1 and 2DW2 prepare the call counting devices of cars A and B for operation. The opening of the contact members 2DW6 prepares the relay 2DX for operation.

75 The energized relay 2DX closes its contact members 2DX3 and thereby effects the energization of the down call registering relay 2DR of car A for the second floor. The closing of the contact members 2DX4 does not affect the call registering relay for car B because its signal zone circuit is open. The energized relay 2DR closes its contact members 2DR1 to prepare for stopping the car A at the second floor on its down trip, in a manner similar to that heretofore described in connection with the other stops.

80 The closing of the contact members 2DR2 of the energized registering relay completes the 20 circuit for again operating the down trip counting relay DH of car A. These closed contact members 2DR2 will remain closed until the call is cancelled. In the meantime, it will be assumed that two other down passengers at the 25 second floor enter the landing at the floor through the gate 51 and consequently pass through the light rays 65 and 64 and actuate the counting relay DH to move its counting mechanism 2 more steps, making a total of three 30 intending down passengers at the second floor.

85 The counting relay DH is adjusted for cutting car A out of any more calls on its down trip after ten intending down passengers have passed through the down entrances and have effected 35 the registration of one or more calls for car A. Inasmuch as seven passengers passed through the down entrance for the third floor and were counted by the counting relay DH and now three more passengers have passed through the down entrance 51 at the second floor and have thereby 40 operated the counting relay DH to count three more persons, that relay has counted a total of ten persons. As stated above, the counting relay DH has been so adjusted that its limit for 45 car A is ten persons. It has now reached the limit of ten persons and therefore operates to open its contact members DH1 and DH2. The opening of the contact members DH1 disconnects the down brush 43 for car A from its zone circuit 67 and thereby prevents the registration of 50 any more down calls for car A for the reason that no energy can be fed into these relays from the supply conductor L-3. The opening of the contact members DH2 (Fig. 8) disconnects the down 55 brush 42 for car A from the zoning contact segments so that car A cannot, while on this down trip, energize any of the zone relays to create a signal zone ahead of itself.

60 It will be assumed now that an intending passenger enters the floor landing at the first floor through the up gate 50 and thus intercepts the light rays 63 and 62 for the lower terminal thereby effecting operation of the corresponding relays 1UW and 1UX. The operation of these relays closes their contact members 1UW3 and 1UW4 and 1UX3 and 1UX4 in the circuits of the call registering relays for both cars A and B. However, as previously described, the contact members DH1 leading to brush 43 of car A are 70 open and, therefore, the up call registering relay for the lower floor for car A cannot be energized even though car A is the nearest approaching car and the contact members 1UW3 and 1UX3 have been closed in the circuit of its call register. 75

ing relay 1UR. Inasmuch as car B (now at the top terminal and above car A) controls the signal zone circuit ahead of itself past car A, the closing of the contact members 1UW4 and 1UX4 (Fig. 7) energize the up call registering relays B1UR of car B by a circuit extending from the supply conductor L+4 through the contact members 1UW4 and 1UX4, coil B1UR, the contact members 2UP2 to zone circuit B67 and thence 10 through the contact members 1UZ2, 2DZ2, 3DZ2 and 4DZ2, contact segment B5h, brush B43 and the contact segments BDH1 to the supply conductor L-4. The energized relay B1UR for car B operates its contact members to light the signal lamp at the lower terminal for car B and to 15 prepare for stopping that car when it approaches within stopping distance of the lower terminal.

By the foregoing operations it will be seen that as soon as the quota of ten persons for car A 20 was filled for its down trip, even though seven of the persons were at one floor and three of the persons were at another floor, the signal system of car A was so controlled by the counting relay DH as to prevent car A from receiving any more 25 down calls on this down trip. It is also seen that when an additional call by the eleventh person was registered, it was registered for car B which is the next approaching car behind car A.

It will be assumed now that one of the elevator 30 passengers steps off a car after it stops and mistakenly walks out through the "up" entrance 50 at the third floor instead of out through one of the "exit" openings at that landing. In walking in and out through the "up" entrance 50, the 35 passenger first intercepts the light rays 62 from the lamp 60 to the light sensitive cell UQ and then the light rays 63. This interception causes the cell UQ to so control its amplifier 71 that the call preventing relay 3UY is energized before the 40 passenger can pass through the light rays 63. The circuit for the relay 3UY extends from the transformer winding 93 through the conductor 94, the coil 3UY, the closed contact members 3UW6, the amplifier 71 and conductor 95 to the 45 winding 93. The energized relay 3UY immediately opens its contact members 3UY1 thereby preventing energization of the call preparing relay 3UW and consequently preventing the registration of stop calls by persons walking out 50 through the "in" entrances 50 marked "up" or out through the "in" entrances 51 marked "down." Hence it is seen that only the passage of passengers in the correct direction through the call operating entrances will be effective to operate 55 the call registering means and the quota counting relays.

At times it may be desirable to operate the cars under pre-registered signals instead of automatically stopping them in response to hall calls. 60 In order to provide for pre-registered signal operation, the signal lamp 103 in car A is disposed to be so controlled by a switch 104 that operation of the stopping relay S in closing its contact members S1 will light the lamp instead of operate 65 the inductor relays E and F. Car B is also provided with a signal lamp B103 and a switch B104. When the pre-registered signal system is in operation, as when the switches 104 and B104 are in their lower positions, the operation of a 70 control or light sensitive device at a floor by an intending passenger will cause the lighting of the signal lamp in the nearest approaching car when it arrives within stopping distance of that floor so that the car attendant may immediately center his car switch to thereby energize the inductor 75

relays and cause the car to decelerate and stop level with that floor in answer to the passenger's stop signal. By the term "nearest approaching car" we mean that car whose position, direction of operation and distance from the floor will permit the car to stop at that floor when it arrives thereat. In other words, it means the nearest car for the desired direction which is still capable of being stopped at the floor for which a stop call is registered at the time of registration. 10

In view of the assumed operation of the system, it will be understood that we have provided an improved elevator system which may be operated with practically no effort on the part of the passengers, which will prevent the crowding of the 15 cars and which will facilitate the answering of the calls and the loading and the unloading of the passengers more efficiently than heretofore.

It will be seen that we have provided a system 20 which will prevent the giving of false stopping signals at the various floors; that is, which will prevent a car from accepting a stop call and giving a stop signal at an additional floor when it has already accepted hall stop calls for all 25 the passengers it can comfortably carry.

Although we have illustrated and described only one specific embodiment of our invention, it is to be understood that many changes therein and modifications thereof may be made without departing from the spirit and scope of the 30 invention.

We claim as our invention:

1. In an elevator system for operating a car serving a plurality of floors, a stopping means for the car, a plurality of standards defining an up entrance and a down entrance leading to the car at each floor, means responsive to the passage of an intending passenger through the up entrance at a floor for operating the stopping means of the car when it approaches within stopping distance of that floor for the up direction to stop it at the floor, and means responsive to the passage of an intending passenger through the down entrance for operating the stopping means of the car when it approaches within stopping distance 40 of the floor in the down direction for stopping it at that floor. 45

2. In an elevator system for operating a plurality of cars serving a plurality of floors, a stopping means for each car, a plurality of walls disposed to provide an up entrance and a down entrance 50 leading to all of said cars at each floor, means responsive to the passage of an intending passenger through the up entrance at a landing for registering a stop call for the nearest approaching car for the up direction, means responsive to the registration of said up call for operating the stopping means of the car for which the call has been registered when it arrives at said floor, and means responsive to the passage of a passenger through the down entrance at a floor for registering a down call for that floor for the nearest approaching car in the down direction, and means responsive to said down registered call for actuating the stopping means of said nearest approaching down car when that car arrives in the down direction within stopping distance of that floor to stop it at that floor. 60

3. In an elevator system for operating a plurality of cars past a plurality of floors, and up control means and a down control means at each of said floors, a plurality of up call registering devices, one for each car for each floor, a plurality of down call registering devices, one for each car for each floor, means responsive to operation of a 70 75

control means at a floor for operating the call registering device of the nearest approaching car in the corresponding direction, a means functionally related to the stopping of the car for each car, means responsive to an operated call registering device for operating said functionally related means for that car; and quota means responsive to operation of the control means by a predetermined number of intending passengers 10 and to the registration of a call for that car for preventing operation of additional call registering devices for that car.

4. In an elevator system for operating a plurality of cars past a plurality of floors, an up control means and a down control means at each of said floors, a plurality of up call registering devices, one for each floor, a plurality of down call registering devices, one for each car for each floor, means responsive to operation of 20 the control means at a floor for operating the call registering device of the nearest approaching car in the corresponding direction, a means functionally related to the stopping of the car for each car, means responsive to an operated 25 call registering device for a car for operating said functionally related means for that car, and quota means responsive to operation of the control means by a predetermined number of intending passengers for said nearest approaching 30 car and to the registration of a call for that car for preventing operation of additional call registering devices for that car and for causing the control devices operated by additional intending passengers for said nearest approaching car to 35 effect the operation of the call registering devices of the next car following said nearest approaching car.

5. In an elevator system for operating a plurality of cars serving a plurality of floors, a stopping means for each car, a plurality of standards defining an up entrance and a down entrance leading to the cars at each floor, an identifying means for the up entrance, an identifying means for the down entrance, means responsive to the 40 passage of an intending passenger through the up entrance at a floor for operating the stopping means of the nearest approaching car for the up direction for that floor when it approaches within stopping distance of that floor, and 45 means responsive to the passage of an intending passenger through the down entrance for operating the stopping means of the nearest approaching car for the down direction when it approaches within stopping distance of the floor.

6. In an elevator system for operating a plurality of cars serving a plurality of floors, a stopping means for each car, a plurality of walls disposed to provide an up entrance, a down entrance and an exit for passengers for said cars at each floor, an identifying means associated with the up entrance, the down entrance and the exit at each floor, means responsive to the passage of an intending passenger through the up entrance at a floor for registering a stop call for the nearest approaching car for the up direction, means responsive to said up registered call for actuating the stopping means of the said nearest approaching up car when that car arrives in the up direction within stopping distance of that floor to stop 55 it at that floor, means responsive to the passage of a passenger through the down entrance at a floor for registering a down call for that floor for the nearest approaching car in the down direction, and means responsive to said down registered call for actuating the stopping means of 60

said nearest approaching down car when that car arrives in the down direction within stopping distance of that floor to stop it at that floor.

7. In an elevator system for operating a plurality of cars serving a plurality of floors, a stopping means for each car, a plurality of call registering devices, one for each car for each floor, a plurality of walls disposed to provide an up entrance, a down entrance and an exit for said cars at each floor, means for identifying the up entrance, the down entrance and the exit at each floor, a plurality of light sensitive devices one for each up entrance and one for each down entrance for each of the floors, light means for illuminating the light sensitive devices, a plurality of call operating relays one for each light sensitive device disposed to be operated by operation of that light sensitive device when an intending passenger passes between that light sensitive device and the light provided for illuminating it, a 10 plurality of zone defining devices operated by and in accordance with the position of the cars, means responsive to operation of a call registering device by an operated light sensitive device at a floor and to operation of the zoning devices 15 for operating the call registering device of the nearest approaching car for the floor of the operated light sensitive device to register a stop call for that car, and means responsive to the registration of a stop call upon the call registering 20 device of that car for operating its stopping means upon its approach to within a predetermined distance of said floor to stop it at that floor.

8. In an elevator system for operating a plurality of cars serving a plurality of floors, a plurality of walls disposed to provide an up entrance and a down entrance common to all the cars at each floor, identifying means for the up entrance and the down entrance at each floor, a stopping means for each car, a plurality of call preparing light sensitive devices one for each entrance, a plurality of call operating light sensitive devices one for each entrance for each floor, means for illuminating the light sensitive devices at each floor by approximately parallel rays of light, a plurality of call preparing relays, one for each of the call preparing light sensitive devices, a plurality of call operating relays one for each of the call operating light sensitive devices, the call 40 preparing relay for each light sensitive device being disposed to be operated by the operation of that light sensitive device in response to the passage of an intending passenger through the light rays to that light sensitive device, the call 45 preparing relay for each entrance being disposed to be operated by the operation of the call preparing relay for that entrance and operation of the call operating light sensitive device with which it is associated by the passage of an intending passenger between the source of light and that light sensitive device, a plurality of call 50 registering relays, one up and one down for each car for each floor, means responsive to operation of a call operating relay for a floor for operating the call 55 registering device for the corresponding direction for the nearest approaching car in the corresponding direction for that floor, and means responsive to operation of that call registering device for operating the stopping means of that car when it approaches within stopping distance of that floor to stop it at that floor.

9. In an elevator system for operating a plurality of cars serving a plurality of floors, a plurality of walls disposed to provide an up entrance 60

and a down entrance each common to all the cars at each floor, an identifying means for the up entrance and an identifying means for the down entrance at each floor, a stopping means for each car, a plurality of light sensitive devices, one at each entrance at each floor, means for illuminating each light sensitive device by light rays at each floor, a plurality of call registering relays, one for each car for each floor, means responsive to the effect on a light sensitive device at a floor produced by the passage of an intending passenger through the light rays to that light sensitive device for operating the call registering relay for that floor for the nearest approaching car for the direction corresponding to that light sensitive device, and means responsive to operation of that call registering device for operating the stopping means of that nearest approaching car when it approaches within stopping distance of that floor to stop it at that floor.

10. In an elevator system for operating a plurality of cars serving a plurality of floors, a plurality of up call registering devices one for each of said cars for each of said floors, a plurality of 15 down call registering devices one for each of said cars for each of said floors, an up passenger operative means and a down passenger operative means at each of said floors, means responsive to operation of a passenger operative means at a 20 floor and to the position of the cars for operating the call registering relay for the direction of the operated passenger operative means for the nearest approaching car for the direction of the operated passenger operative means for that floor, 25 and means responsive to operation of said passenger operative means by a predetermined number of intending passengers and to operation of said operated call registering relay for preventing operation of additional call registering devices 30 for said nearest approaching car.

11. In an elevator system for operating a plurality of cars past a plurality of floors, an up control device and a down control device at each floor, common to all the cars, a plurality of call 45 registering devices one for the up and one for the down direction for each car for each floor, means responsive to operation of a control device at a floor for operating the call registering device for the direction of the operated control device of the 50 nearest approaching car for the direction of the operated control device for that floor, a stopping means for each car, means responsive to the approach of said nearest approaching car to the floor corresponding to said operated control device and to said operated call registering device for operating the stopping means for that car, and means responsive to operation of said operated control device by a predetermined number 55 of passengers for said nearest approaching car and to operation of said operated car registering device for preventing the operation of additional call registering devices for that car by operation of the control devices at floors between that car and the next car ahead.

60 12. In an elevator system for operating a plurality of cars serving a plurality of floors, an up control device and a down control device at each floor common to all the cars, a plurality of up call registering devices one for each car for each floor, a plurality of down call registering devices 65 one for each car for each floor, an up counting device and a down counting device for each car, a zoning means for the cars, means responsive to operation of the zoning means and to operation of a control device at a floor for operating the

call registering device for the direction of the operated control device for the nearest approaching car for the direction of the operated control device, means responsive to the operation of the operated control device and to operation of the 5 operated call registering device for operating the counting device for the direction of the operated control device of said nearest approaching car, and means responsive to operation of said operated counting device a predetermined number of 10 times for preventing operation of additional call registering devices for said nearest approaching car.

13. In an elevator system for operating a plurality of cars serving a plurality of floors, an up 15 control device and a down control device at each floor common to all the cars, a plurality of up call registering devices, one for each car for each floor, a plurality of down call registering devices, one for each car for each floor, an up counting 20 device and a down counting device for each car, means for providing a zone for each of the cars, means responsive to operation of the zoning means and to operation of the control device at a floor for operating the call registering device for the direction of the operated control device for that operated control device, means responsive to operation of the operated control device and to operation of the 25 operated call registering device for operating the counting device corresponding to the direction of the operated control device for said nearest approaching car, means responsive to operation of the operated counting device a predetermined number of times for preventing operation 30 of additional call registering devices for said nearest approaching car and for conditioning the zoning means to cause the operation of additional control devices of the direction of the operated control device in the zone of said nearest approaching car to operate the call registering device for the direction of the operated control 35 device of a following car.

14. In an elevator system for a plurality of cars serving a plurality of floors, means defining an up entrance and a down entrance leading to the cars at each floor, a plurality of light sensitive devices, one for each up entrance and one for each down entrance at each of the floors, light means for illuminating the light sensitive devices, a means functionally related to the stopping of the car for each car, means responsive to operation of a light sensitive device for an up entrance at a floor by the passage of an intending passenger through said up entrance for operating the means functionally related to the stopping of the nearest approaching car for the up direction for said floor, and means responsive to operation of a light sensitive device for a down entrance at a floor by the passage of an intending passenger through said down entrance for operating the means functionally related to the stopping of the nearest approaching car for the down direction for said floor.

65 15. In an elevator system for a plurality of cars serving a plurality of floors, means defining an up entrance and a down entrance leading to the cars at each floor, a plurality of light sensitive devices, one for each up entrance and one for each down entrance at each of the floors, light 70 means for illuminating the light sensitive devices, a means functionally related to the stopping of the car for each car, a signal device for each car for each entrance at each floor, means responsive to operation of a light sensitive device for

an up entrance at a floor by the passage of an intending passenger through said up entrance for immediately operating the up signal device of the nearest approaching car for the up direction for that floor and for operating the means functionally related to the stopping of that car when it arrives within stopping distance of that floor, and means responsive to operation of a light sensitive device for a down entrance at a floor by

the passage of an intending passenger through said down entrance for immediately operating the down signal device of the nearest approaching car for the down direction for that floor and for operating the means functionally related to the stopping of that car when it arrives within stopping distance of that floor.
